FIG. 5

FIG. 1 is a rear perspective view of a knapsack showing my new design, it being understood that the partial fabric shading is uniform;

FIG. 2 is an enlarged, fragmentary view of the upper right hand portion of FIG. 1;

FIG. 3 is a front elevation view thereof;

FIG. 4 is a side elevation view thereof, the shoulder straps being in a wearing position; and

Conventional shading is employed on the shoulder straps to indicate color contrast rather than any specific color.

I claim:

The ornamental design for a knapsack, substantially as shown and described.
